UNITED STATES PATENT OFFICE.

LOUIS A. PICAL, OF PARMA, OHIO.

FLY-CATCHING DEVICE.

Application filed March 27, 1925. Serial No. 18,745.

To all whom it may concern:

Be it known that I, LOUIS A. PICAL, a citizen of France, residing at Parma, in the county of Cuyahoga and State of Ohio, have 5 invented certain new and useful Improvements in a Fly-Catching Device, of which the following is a specification.

The present invention relates to a device for catching flies and the like, and aims to 10 provide a novel and improved device of this character having a continuous adhesive coated belt which may be conveniently moved about rollers for presenting a clean surface thereof in order that more flies may 15 be caught, said device being so arranged that flies caught on the belt are scraped therefrom and a fresh supply of adhesive provided on the belt before that portion of the same is again brought to a fly catching 20 position.

Another object of the invention is the provision of a blade positioned below the continuous fly catching belt and arranged in a removable drawer in order that flies 25 scraped from the belt by the turning thereof to present a clean surface will be deposited into the drawer, which when removed may be scalded to efficiently clean the same, said blade being mounted on a pivot in the 30 drawer to permit the same to be swung to engage the belt or to a position away from said belt.

A still further object of the invention is to provide a casing about the movable parts 35 of the device, having an enlarged opening in the top wall thereof for exposing a relatively large portion of the continuous adhesive coated belt in order that flies may be caught thereon, said exposed portion of 40 the belt lying adjacent said opening for preventing flies and other matter from gaining access to the interior of the device unless the same are caught on the belt.

It is also an object of the invention to provide 45 a fly catching device of the kind indicated, which is simple and substantial in construction, which may be manufactured economically, and which will be thoroughly efficient and practical in use.

With the foregoing and other objects in view, which will be apparent as the description proceeds, the invention resides in the construction and arrangement of parts, as hereinafter described and claimed, it being

understood that changes can be made within 55 the scope of what is claimed without departing from the spirit of the invention.

The invention is illustrated in the accompanying drawings, wherein:

Figure 1 is a top plan of my improved device, 60

Figure 2 is a side elevation thereof,

Figure 3 is a longitudinal vertical section through the same,

Figure 4 is a vertical cross section taken 65 on line 4—4 of Figure 3,

Figure 5 is a top plan of my improved device with the cover removed and showing portions of the device broken away,

Figure 6 is a cross section taken on line 70 6—6 of Figure 3,

Figure 7 is a fragmentary vertical section on line 7—7 of Figure 6,

Figure 8 is also a fragmentary section taken on line 8—8 of Figure 6, 75

Figure 9 is a detail section of the pawl and ratchet mechanism arranged on one of the rollers, being taken on line 9—9 of Figure 6,

Figure 10 is a fragmentary section on line 80 10—10 of Figure 2, through the front wall of the removable drawer,

Figure 11 is a section taken on line 11—11 of Figure 10, and

Figure 12 is a detail fragmentary section 85 showing the manner in which the removable cover is attached to the casing.

In carrying out the invention, the numeral 15 designates a rectangular casing having side walls 16, end walls 17, and a bottom 18, said bottom having a depression provided at each corner thereof in order to provide supporting feet 19 for contacting with the surface upon which the rectangular casing rests. Positioned upon the upper portion of 90 the rectangular casing is a cover 20 having a continuous downwardly extending flange 21 thereon for engaging about the upper portions of the side and end walls. Attached to the flange 21 at one end of the cover is an angled member 22 in order to provide a hand 95 engaging portion for removing the cover, said angled member and end flange being provided with aligning openings 23 through which a short pin 24 carried by the end wall 100 17 of the casing extends, while at the opposite ends of the casing the other end wall 17 is provided with indentations 25 into which

engage struck out portions 26 provided in the end flange 21 engaging with said end wall 17.

The major portion of the top wall of the cover 20 is cut away in order to provide an enlarged rectangular opening 27, the purpose of which will be understood as the description proceeds, the edges of said opening being provided with smooth rounding surfaces, constructed by turning portions of the material from which the cover is made back upon itself, as at 28.

Positioned in the rectangular casing 15 at each end thereof and extending between the side walls 17 are a pair of rollers 29 and 30, each having an annular flange 31 formed at each end thereof. At the pivot point of the rollers, the side walls 17 of the casing are struck inwardly to provide rounding surfaces that engage the ends of the rollers, said struck in portions 32 having pins extending therethrough and into the rollers, as at 33, to provide the means for pivotally or rotatably supporting the same. Over the roller 29 and the roller 30 is trained a continuous belt 34, which is constructed of canvas or the like. In order to prevent the belt from slipping on the roller 29, I have provided a pair of annular bands 35 secured about the roller and having outwardly directed prongs 36 for frictionally engaging the belt, while on the roller 30 is provided a metallic sleeve 37 having like struck out portions 38 thereon. One of the pins 33 that rotatably supports the roller 30 extends outwardly and is provided with a crank portion 39 which may be engaged by the operator in order to rotate the roller 30 to turn the continuous belt 34 thereover.

One of the flanges on the roller 30 is of narrower construction than the remaining flanges in order that a series of outwardly directed teeth 40 carried by an annular band 41 may be secured to said roller 30, said teeth being provided for engaging a pawl 42 carried by one of the end walls 17 in order to prevent retrograde movement of the roller.

Positioned in the casing 15 intermediate its ends and extending across the same is a platform 43 for supporting the portion of the continuous belt 34 that is exposed through the opening 27, said platform having secured to each end thereof a cross rod 44, the opposite ends of which extend downwardly as at 45, and are received in sockets 46 of the brackets 47 secured to the opposite side walls 17 of the casing. The opposite side edges of the platform 43 are bent upwardly and slightly back upon the platform in order to slightly overlap the same, as at 48, to provide grooves through which the opposite side edges of the continuous belt slide. Adjacent the ends of the opening 27 at the end of the casing where the roller 30 is

mounted is provided a series of a slightly curved downwardly extending pins 49 that contact with the continuous belt at all times.

In the end wall 17 below the roller 30 is provided a rectangular opening 50 through which a slidable drawer 51 extends, said drawer having an outwardly extending flange 52 arranged at each end thereof and adjacent the top thereof, which are slidably positioned between the spaced inwardly extending flanges 53 carried by the side walls 17 of the casing, which structure provides a guide for slidably supporting the drawer. Spaced slightly from the opposite end walls 54 of the drawer are provided plates 55 that are secured to the bottom of the drawer, as at 56, and are provided with vertical slots 57 into which are received the trunnions 58 of an adhesive roller 59 positioned in the drawer. The upper ends of the plates 55 are bent outwardly and over the end walls of the drawer to provide abutment members 60 that contact with the end wall 17 to limit the outward movement of the drawer, said outwardly bent portions having extension portions 61 carried thereby which extend over the upper ends of the slots 57 for engaging the trunnions 58 to prevent the adhesive roller from moving out of the slots 57. Attached to the bottom of the drawer 51, as at 62, are leaf springs 63, the upper ends of which are turned about the trunnions 58 in order to normally hold the adhesive roller 59 in an upward position and in contact with the belt 34 for applying adhesive thereto when the adhesive roller is rotated due to the movement of the belt, as the drawer 51 contains the adhesive matter in a liquid form.

The outer portion of the drawer 51 is provided with a continuous flange 64 that engages the outer surface of the end wall 17 to limit the inward movement of the drawer, while a handle 65 is attached to the drawer for manually sliding the same to an outward or inward position. It will be noted that when the drawer 51 is moved to its inward position that the adhesive roller 59 is slightly inward of the roller 30 so that the contacting of the rollers will provide a means for holding the drawer in a closed position, and that when the drawer is opened, the roller contacts with the upper edge of the opening 50 in the wall 17 and is positioned slightly outward of such opening so that the drawer will be yieldably held in its open or outward position.

In one of the side walls 17 of the rectangular casing 15 is provided an opening 66 in which is slidably mounted a drawer 67, which when positioned in the casing extends below the continuous adhesive coated belt 34, said drawer being guided during its sliding movement by the provision of outwardly extending flanges 68 provided upon the

lower side walls of the drawer for engaging in grooves 69 constructed by overlapping the opposite side edges of a plate 70 secured to the bottom wall 18 of the casing. Extending between the opposite end walls of the drawer and pivotally received therein is a rotatable bar 71 to which is secured a blade 72, which is adapted to be swung upwardly into engagement with the continuous belt 34 in order to scrape flies and the spent adhesive matter from the belt during the turning movement thereof over the rollers 29 and 30. When the blade 72 is in an upward position, as indicated in dotted lines in Figure 3, the same contacts with the stop members 73 in order to prevent the belt from swinging the blade past its scraping position. On the outer end of the bar 71 is a head 74 which has the side walls thereof arranged at right angles to each other for providing flat surfaces that are engaged by inwardly turned portions 75 of a lever 76, in order to secure the lever 76 to the rod 71. Upon the extreme outer end of the rod 71 is positioned a knob 77 which may be grasped by the fingers of the operator in order to swing the blade 72 in an upward position to contact the same with the belt 34. Secured upon the free end of the lever 76 is a small hand engaging knob 78 so that the lever may be engaged for turning the rod 71, said lever also having an inwardly directed pin 79 carried thereby for engaging in an opening 80 in the front wall of the drawer for holding the blade in its upward position.

In operation, the device remains in a stationary position until a considerable number of flies have been caught on the upper side of the upper portion of the belt, the flies having passed through the opening 27 in the cover of the casing. The crank handle 39 is then turned in an anti-clockwise direction, causing the continuous belt 34 to be moved about the rollers 29 and 30, the blade having been moved to its upward position into engagement with the belt, which will cause the flies and spent adhesive to be scraped from the belt and deposited in the drawer 67. After the belt has been scraped, the adhesive roller 59 contacts therewith, supplying a new quantity of adhesive over the outer surface of the belt, as the lower portion of the roller 59 is positioned in the liquid adhesive carried in the drawer 51. The turning movement of the crank is continued until a clean surface of the belt is brought below the opening 27. When in this position the blade 72 is swung to its downward position into the drawer 67 and the drawer is then removed from the casing in order that the flies and spent adhesive matter may be removed therefrom, by scalding same.

From the foregoing it can be seen that a

fly catching device is provided whereby a clean surface of fly catching adhesive may be positioned below the opening 27 when desired, and that by simply turning the crank 39 the device is ready for another catch. 70

Having thus described my invention, what I claim as new is:

1. A device of the character described comprising a casing having an enlarged opening therein, a roller rotatably mounted at each end of said casing, a belt trained about said rollers and lying below said opening, means attached to one of said rollers for rotating the same in order to turn the belt, a drawer arranged in one end of said casing for containing a liquid adhesive, an adhesive roller positioned in said drawer, and spring means engaging said roller for holding the same in contact with said belt in order to apply adhesive thereto during the turning of said belt. 80 85

2. A device of the character described comprising a casing having an enlarged opening therein, a roller rotatably mounted at each end of said casing, a belt trained about said rollers and lying below said opening, means attached to one of said rollers for rotating the same in order to turn the belt, a drawer arranged in one end of said casing for containing a liquid adhesive, an adhesive roller positioned in said drawer, and spring means engaging said roller for holding the same in contact with said belt in order to apply adhesive thereto during the turning of said belt, said adhesive roller 90 95 engaging the belt at a point adjacent one of the first mentioned rollers and slightly inward thereof in order to yieldably hold the drawer in a closed position. 100

3. A device of the character described comprising a casing having an enlarged opening formed in the top wall thereof, a roller rotatably mounted at each end of said casing, a belt trained about said rollers and having the upper portion thereof lying adjacent said opening in said casing, means attached to one of said rollers for rotating the same in order to turn said belt, said casing having another opening formed in one end wall thereof, a drawer slidably 110 115 mounted in said second mentioned opening, an adhesive roller positioned in said drawer, a pair of spring members one arranged at each end of said adhesive roller for holding the same in engagement with said belt, and means for guiding the movement of said roller by said spring members. 120

4. A device of the character described comprising a casing having an enlarged opening formed in the top wall thereof, a roller rotatably mounted at each end of said casing, a belt trained about said rollers and having the upper portion thereof lying adjacent said opening in said casing, means attached to one of said rollers for rotating 125 130 135

the same in order to turn said belt, said casing having another opening formed in one end wall thereof, a drawer slidably mounted in said second mentioned opening, 5 an adhesive roller positioned in said drawer, a pair of spring members one arranged at each end of said adhesive roller for holding the same in engagement with said belt, and means for guiding the movement of said roller by said spring members, said adhesive roller being adapted to engage the upper edge of said second mentioned opening and lie slightly on the outside thereof in order to yieldably hold the drawer in an 10 open position to permit a liquid adhesive to be supplied to said drawer.

5. A fly catching device of the character described comprising a casing having an enlarged opening in the top wall thereof, a 15 roller rotatably mounted at each end of said casing, a belt trained about said rollers and having a portion thereof lying in close proximity to said opening in said casing, means for rotating one of said rollers for turning said belt, means for applying an adhesive to said belt as the same is turned, said casing having an opening in one side wall thereof, a drawer slidably mounted in 20 said opening, a blade pivotally mounted in said drawer and adapted to be swung to a position to engage the belt for removing flies therefrom upon turning movement thereof for depositing the flies into the drawer.

6. A fly catching device of the character described comprising a casing having an enlarged opening therein, a pair of rollers one rotatably mounted in each end of said casing, a belt trained about said rollers and having a portion thereof lying in close proximity to said opening, means for rotating one of said rollers for turning said belt, 25

means for applying an adhesive to said belt as the same is turned, said casing having an opening formed in one side wall thereof, a 45 removable drawer slidably mounted in said opening and adapted to lie below the belt, a rod pivotally mounted in said drawer, a blade attached to said rod and adapted to be brought into engagement with the belt for scraping flies therefrom, a lever attached to one end of said rod for operating the movement of the blade, and means for holding said lever in a position with the blade in engagement with the belt. 50

7. A fly catching device of the character described comprising a casing having an enlarged opening therein, a pair of rollers one rotatably mounted in each end of said casing, a belt trained about said rollers and having a portion thereof lying in close proximity to said opening, means for rotating one of said rollers for turning said belt, means for applying an adhesive to said belt as the same is turned, said casing having an opening formed in one side wall thereof, a removable drawer slidably mounted in 55 said opening and adapted to lie below the belt, a rod pivotally mounted in said drawer, a blade attached to said rod and adapted to be brought into engagement with the belt for scraping flies therefrom, a lever attached to one end of said rod for operating the movement of the blade, means for holding said lever in a position with the blade in engagement with the belt, and stops formed on said drawer to be engaged by the blade to prevent the same from being swung past its position for engaging the belt. 60

In testimony whereof, I have affixed my signature.

LOUIS A. PICAL.
